Boyers, Pa

The United States of America,

TO ALL TO WHOM THESE Letters Patent SHALL COME:

Whereas Jacob Fuller a Citizen of the United States hath alleged that he has invented a new and useful improvement

in the Machine for shelling Indian Corn

Which improvement he states has not been known or used before his application; hath made oath that he does verily believe that he is the true inventor or discoverer of the said improvement; hath paid into the treasury of the United States the sum of thirty dollars, delivered a receipt for the same, and presented a petition to the Secretary of State, signifying a desire of obtaining an exclusive property in the said improvement, and praying that a patent may be granted for that purpose: These are therefore to grant, according to law, to the said Jacob Fuller his heirs, administrators or assigns, for the term of fourteen years, from the nineteenth day of March one thousand eight hundred and sixteen the full and exclusive right and liberty of making, constructing, using, and vending to others to be used, the said improvement; a description whereof is given in the words of the said Jacob Fuller himself, in the schedule hereto annexed, and is made a part of these presents.

In Testimony whereof, I have caused these Letters to be made Patent, and the Seal of the United States to be hereunto affixed.

G I V E N under my hand, at the City of Washington, this nineteenth day of March in the year of our Lord One Thousand Eight Hundred and sixteen and of the Independence of the United States of America, the fourteenth.

James Madison

BY THE PRESIDENT.

James Monroe Secretary of State,

City of Washington, To Wit.

I DO HEREBY CERTIFY, That the foregoing Letters Patent were delivered to me on the nineteenth day of March in the year of our Lord, One Thousand Eight Hundred and sixteen to be examined; that I have examined the same, and find them conformable to law: and I do hereby return the same to the SECRETARY OF STATE, within fifteen days from the date aforesaid, to wit; on this nineteenth day of March in the year aforesaid.

Richard Rush - Attorney General of the United States

Colje Schidle, referred to in these Letters patent and
making part of the same containing a description in the words of the said
Jacob Fuller himself of his Machine for shelling Indian corn —

This Machine consists of a principal Cylinder the axis of which rests on the horizontal beams of the frame which supports the various parts of the Machine its surface is covered entirely with small plates of cast iron or hard wood with spikes in it fastened across wise on the Cylinder that is in the direction of the axis from these iron plates project a number of protuberances, which when the Machine is in motion operate on the corn in such a manner as to separate the grain from the ^{the lower part of the} Cob. The grain is incircled by a number of Staves or leaves attached to one another by hinges placed at the extremities of the leaves they form a semicircle round the lower convex of the Cylinder and are placed about an inch and a half distant from it. The concave of this semicircle is studded with iron spikes similar to those on the surface of the Cylinder; and every respective leaf which constitutes a part of it rests upon a spring those springs when the semicircle is pressed on by the compeling between it & the Cylinder yield in proportion of the pressure and make room for the corn to pass through. A small spur wheel is attached to one end of the axis of the Cylinder and is operated on by a larger one fixed at the extremity of the frame which when turned communicates motion to the whole machine. The ears of Corn are received at the upper end of the Semicircle which surrounds the lower part of the Cylinder passing downwards between that and the Cylinder the grain is separated from the Cob by the Co-
operating spikes with which the surface of the Cylinder, and concave of the semicircle are studded. The grain falls through an aperture made in the lower part of the Semicircle and grates with small iron bars and the cobs are discharged separately at the lower extremity of the semicircle. The Machine is supplied by a hopper placed at the upper extremity of the semicircle, a small fan is placed near the aperture through which the grain falls when separated from the Cob this fan is turned when the Machine is in operation and cleanses the grain from any dust that may be connected with it.
